UNITED STATES PATENT OFFICE

RANDOLPH J. BUEHLER, OF BOSTON, MASSACHUSETTS

VALVE ACTUATING MECHANISM

Application filed September 26, 1927. Serial No. 222,113.

The invention relates to valve actuating mechanisms and particularly to means controlling the gas and oil valves of an oil burner in predetermined timed relation, and has for its object to provide a thermostatically controlled motor cooperating with a gas supply valve and an oil supply valve whereby upon operation of the motor said gas supply valve will be opened for supplying gas to the burner and the oil supply valve will have a slow opening action, whereby a full supply of oil will not be supplied to the burner until the burner is preheated by the gas and initial small supply of oil. A further object is to close the gas supply valve as the oil supply valve approaches fully open position. A further object is to provide the motor shaft with a cam cooperating with a pivoted lever having a link connection with one valve, and which cam rotates slowly and is provided with a link connection with the second valve, and forms means whereby on its initial rotation the first valve is rapidly opened and the oil valve slowly opened, said oil valve being entirely opened after a movement of the cam for substantially one hundred and eighty degrees, and at which time the gas valve is closed. With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a top plan view of the valve control mechanism.

Figure 2 is a side elevation of the valve control mechanism.

Referring to the drawing the numeral 1 designates an electric motor, which motor is provided with a shaft 2, which is slowly rotated, for instance whereby it will make a half revolution in from five to ten minutes, and the speed of which shaft may be controlled by reduction gearing within the

motor, or by any suitable means reducing the motor speed, or both. The motor 1 is controlled by means of a rotatable disc switch 3, which at predetermined periods will close a circuit through the spring contact arms 4 and 5, or through spring contact arms 6 and 5, for operating said motor. Disposed adjacent the motor 1 is a gas supply pipe 12, which pipe is provided with a conventional form of plug valve 13 having an arm 14, and it will be noted by referring to Figure 2 upon the initial rotation of the plug valve 13, its port 15 will be quickly moved to open position, thereby allowing a full flow of gas through the pipe 12 to a burner to be preheated or started by the gas. Pivoted connected to the arm 14 of the plug valve is a link 16, which link is pivotally connected at 17 to a pivoted lever 18, and which lever has its free end adjacent to the motor shaft 2, and is forced into engagement with the cam 19 by means of an expansion spring 20, therefore it will be seen that as the cam 19 is rotated in engagement with the arm 18, the link 16 will be forced downwardly for opening the gas valve. The shaft 2 is provided with an arm 21, to which is adjustably connected at 22 a link 23, and which link is pivotally connected at 24 to an arm 25 carried by a threaded needle valve 26, and which needle valve has a relatively slow opening operation in comparison to the rapid opening of the gas valve 13, whereby the gas will be supplied to the burner well before the oil through the oil supply pipe 27, controlled by the needle valve 26. Upon movement of the cam 19 to the dotted line position *a*, which is a distance substantially ninety degrees, the gas valve 13 will be entirely on, while the oil valve will be only slightly opened, and upon movement of the cam 19 to the dotted line position *b*, the gas valve 13 will be closed and the oil valve will be entirely on, therefore it will be seen that the gas is supplied to the burner for preheating purposes a substantial time before a full supply of oil is supplied to the burner. The oil pressure is controlled by means of the hand operated valve 48. The motor 1 is controlled by a suitable ther-

mostat (not shown), disc switch 3 and spring contact arms 4, 5 and 6 in a manner whereby it will operate only sufficiently to rotate shaft 2 one-half of a revolution or 180 degrees at 5 one time. Thus, when the motor circuit is closed, as through switch 3 and contact arms 5 and 6, the gas valve 13 and the oil valve 26 both being closed, the shaft 2 and cam 19 and arm 21 carried thereby are rotated for 180 10 degrees to dotted line position *b*, quickly opening and then closing gas valve 13 and slowly opening the oil valve 26, whereby at the end of the 180 degree movement of shaft 2 only the oil valve will be open. Subsequently, upon reestablishing the motor circuit, as through switch 3 and contact arms 4 and 5, the motor is again operated to rotate shaft 2 one-half revolution. This second 15 half revolution moves arm 21 carried by shaft 20 2 to its starting position, whereby oil valve 26 is closed. The gas valve is not operated by this second movement of shaft 2 inasmuch as the gas valve operating lever 18 rides upon the end of cam 19 concentric of shaft 2. In 25 this way the motor operated shaft 2 operates and controls valves 13 and 26 in predetermined timed relation as required in the operation of the oil burner.

The oil supply pipe 27 is provided with a 30 valve 44 having a control lever 45 on which is suspended an overflow bucket 46, and into which bucket any excess oil is discharged by the overflow pipe 47, which leads from the burner and discharges into the bucket, therefore it will be seen in case of flooding, or failure of the gas or ignition through any cause, the oil supply will be cut off.

The invention having been set forth what 35 is claimed as new and useful is:—

40 1. The combination with a motor having a shaft, a plug valve adjacent said motor, a screw adjacent said motor, a cam carried by said motor shaft, a member connected to the plug valve and with which the cam operates 45 whereby said plug valve will be opened upon partial rotation of the cam, an arm carried by the screw valve, a link connection between said arm and the cam and forming means whereby upon rotation of the cam substantially one hundred and eighty degrees said screw valve will be in opened position and the plug valve in closed position.

50 2. The combination with a motor having a shaft, a plug valve adjacent said motor, a threaded valve adjacent said motor, a cam carried by said motor shaft, a pivoted member with which said cam engages, spring means for forcing the pivoted member towards the cam, an arm carried by the plug valve, a link connection between the plug valve arm and the pivoted member, an arm carried by the threaded valve, and a link connection between said last named arm and the cam.

55 3. The combination with a motor having a

shaft, a pair of valves having operating arms, of a cam carried by the motor shaft, a cam-engaging member, means connecting said cam-engaging member and one of said valve arms, and means carried by the other valve arm and pivotally secured to said cam.

60 4. The combination with a motor having a shaft, a pair of valves having operating arms, of a cam carried by the motor shaft, a cam-engaging member, an operative connection between said cam-engaging member and one of said valve arms, and cams carried by the other valve arm and pivotally secured to said shaft eccentrically thereof, said connections being arranged whereby upon each rotation of said shaft one of said valves will be quickly opened and closed by said cam-engaging member and the other valve will be slowly opened and closed by said last named means.

65 5. The combination with a pair of valves, arms carried by said valves, of a motor having a shaft, a cam carried by said shaft, a pivoted member adjacent the cam, spring means maintaining said pivoted member in engagement with the cam, a link connection between the pivoted member and the arm of one of said valves, and a link pivotally secured to said cam and the arm of the other valve, said first named link operating one of said valves upon depression of said pivoted member by the nose of said cam, and said last named link operating the other valve at all times in the rotation of said shaft.

70 6. The combination with a pair of valves, arms carried by said valves, of a motor having a shaft, a cam carried by said shaft, means carried by one of said arms and engaging the periphery of said cam to operate one of said valves upon engagement of the cam nose therewith, and means carried by the other arm and pivotally secured to said shaft eccentrically thereof to open said valve upon a half revolution of the shaft and to close said valve upon the succeeding half revolution of the shaft.

75 In testimony whereof I affix my signature.
RANDOLPH J. BUEHLER.
